DESIGN FOR A DUPLICATING MACHINE

Harvey J. Reardon, Chicago, Ill.

Application July 14, 1936, Serial No. 63,836

Term of patent 7 years

To all whom it may concern:

Be it known that I, Harvey J. Reardon, a citizen of the United States of America and a resident of Chicago, in the county of Cook and State of Illinois, have invented a new, original, and ornamental Design for a Duplicating Machine, of which the following is a specification, reference being had to the accompanying drawing forming a part thereof, and in which:

Fig. 1 is a perspective view of a duplicating machine embodying my new design;

Fig. 2 is a side elevational view of the same; Fig. 3 is also a side elevational view but showing the opposite side of the machine from that seen in Figs. 1 and 2; and

Fig. 4 is an end elevational view thereof.

I claim:

The ornamental design for a duplicating machine as shown.

HARVEY J. REARDON.
